(57) **CLAIM**

I claim the ornamental design for a refrigeration substructure for LED lighting, as shown and described.

DESCRIPTION

FIG. 1 is a top perspective of the preferred embodiment. FIG. 2 is an enlarged end view of the preferred embodiment. FIG. 3 is an enlarged cross section view taken along line 3-3 in FIG. 1.

FIG. 4 is a top view of the preferred embodiment.

FIG. 5 is a side view of the preferred embodiment; and, FIG. 6 is a bottom view of the preferred embodiment.

The broken lines shown in the drawings illustrate unclaimed portions of the refrigeration substructure for LED lighting and environmental structure and form no part of the claimed design. The design is shown broken away in the middle of the FIGS. to indicate that the design has a non-specified length.
